[57] CLAIM

The ornamental design for a urinal, as shown and de-
scribed.

DESCRIPTION

FIG. 1 is a perspective view taken from the top, front
and right side of a urinal showing my new design;

FIG. 2 is a top, plan view thereof;

FIG. 3 is a right side elevational view thereof, the left
side being a mirror image of the right side;

FIG. 4 is a front elevational view thereof;

FIG. 5 is a rear elevational view thereof; and,

FIG. 6 is a bottom, plan view thereof.

FIG. 1

FIG. 2

FIG. 3FIG. 4FIG. 5FIG. 6
